UNITED STATES PATENT OFFICE

NELSON S. WELK, OF ATHENS, OHIO, ASSIGNOR TO THE MCBEE BINDER CO., OF ATHENS,
OHIO, A CORPORATION OF OHIO

COMPRESSOR PLATE FOR FILING TRAYS

Application filed July 22, 1927. Serial No. 207,606.

My invention relates to the stationery art, and particularly to trays and containers for receiving cards, and the like, for filing.

The object of my invention is to provide new and adequate means for creating pressure on filed cards and insuring the maintenance of such pressure at all times when the tray is being moved. Experience has proven that undesired displacements of filed cards have occurred by the moving and shifting of the tray holding the cards, and my device is adapted to completely overcome such a possibility.

My invention consists of certain details of construction hereinafter set forth, pointed out in my claims, and illustrated in the accompanying drawings, in which—

Fig. 1 is a plan view of my improved device;

Fig. 2 is a longitudinal cross-section, taken on line 2—2 of Fig. 1; and

Fig. 3 is a detail view, partly in section, of my improved device.

Referring to the accompanying drawings, the reference numeral 10 is used to indicate a filing tray of the usual construction with base and sides, the bottom thereof containing the customary construction of spaced runners 11 on which the cards, sheets, or the like, rest, a securing rod 12 for perforated cards (not shown) extending longitudinally between the spaced runners 11. Thus far my filing tray does not differ from the construction I have heretofore been using, as disclosed in my copending applications, Serial Nos. 90,477 and 90,478.

The numeral 13 indicates my improved compressor plate, hinged at 14 to a mounting 15, said mounting 15 curving upwardly in the space between the runners 11, the upward portion containing the hinge 14, so that the plate 13 is secured below the runners 11. The mounting 15 is secured to the front of the drawer. The compressor plate 13 is mounted near the forward part of the tray, as shown. A handle 16 is pivotally mounted to brackets, 17 and 18, secured to the inner surface of the front of the tray, a rod 19 (in the construction shown) passing through the handle 16 and orifices in the brackets 17 and

18, thus completing the pivotal mounting mentioned. The handle 16 extends through an opening 20 in the front of the tray, thus providing for the forward part of the handle 16 lying outside the front of the tray. 55 Means, preferably consisting of rollers 21, is mounted transversely across the inner end of the handle 16, and, when the handle 16 is rotated to a substantially horizontal position, engage the compressor plate 13, forcing it rearwardly from its pivotal mounting and producing pressure against the filed cards, or sheets. Vertical strip members 22, secured to the front of the compressor plate 13 and bent outwardly at their lower ends to form stops 22^a, provide bearing surfaces for rollers 21 and limit the downward movement of said rollers said stops 22^a being so arranged that when the handle 16 engages them the compressor plate 13 is in a substantially vertical position against the filed cards, or sheets. 60 65

My construction is such, and the parts are so correlated in their positioning, that the whole surface of the compressor plate 13 engages the filed sheets, for, it will be remembered, the hinge of the compressor plate 13 is below the bottom of the sheets, thus causing the lower part of the plate 13 to move rearward from its pivotal mounting when forced by the engagement of the handle 16. 70 75 The handle 16 is of such a size that, when it engages the stops 22^a, the inner end of the handle 16 will lie slightly below the plane of the pivotal mounting of said handle, and it is also constructed so that the portion of the handle 16 lying forward of the pivotal mounting is slightly more in weight than the portion lying to the rear of the pivotal mounting. It is obvious that, by such construction, when the handle 16 is forced against the compressor plate 13, moving it rearwardly against the papers, it, will, when it engages the stops 22^a on the compressor plate 13, be automatically maintained in that position, but a slight downward pressure on the outer end of the handle 16 will immediately release it, and the handle 16, of its own weight, will rotate on its pivotal mounting, thus releasing the compressor plate 13. 80 85

In my drawings I have disclosed a pre- 100

ferred construction, but my invention is susceptible of several different constructions, and I do not want to be limited in the scope of my protection, except as set forth in the appended claims.

Having thus described my invention, what I regard as new, and desire to secure by United States Letters Patent, is:

1. In a filing tray, a base, sides and ends, a compressor plate, hinged to the base below the plane of the bottom of the filing cards; the front end of the tray being provided with an opening; a handle member extending through the opening and pivotally mounted on the inner face of the front end, said handle extending upwardly beyond the pivotal mounting to engage the front surface of the compressor plate.
2. A In a filing tray, a base, sides and ends, a compressor plate, hinged to the base below the plane of the bottom of the filing cards; the front portion of the tray being provided with an opening therein; a handle extending through the opening and pivotally mounted on the inner face of the front portion, a roller mounted transversely across the inner end of said handle; said handle extending upwardly beyond the pivotal mounting so that the roller engages the front surface of the compressor plate.

NELSON S. WELK.
